URINAL

Gerard D. Phillips, Jr., Prospect, Ky., assignor to American Radiator & Standard Sanitary Corporation, New York, N.Y., a corporation of Delaware

Filed Apr. 16, 1962, Ser. No. 69,717

Term of patent 14 years

(Cl. D4—5)

FIGURE 1 is a top plan view of a urinal, showing my new design;

FIGURE 2 is a view in front elevation thereof;

FIGURE 3 is a view in side elevation facing FIGURE 1;

FIGURE 4 is a view in section on the line 4—4 of FIGURE 1, and

FIGURE 5 is a view in section on the line 5—5 of FIGURE 2.

The side not shown is substantially like the side shown.

The rear not shown is flat and plain, except as shown in FIGS. 4 and 5.

I claim:

The ornamental design for a urinal, substantially as shown and described.
